(57) CLAIM

The ornamental design for a bra and panty set, as shown and described.

DESCRIPTION

FIG. 1 is a front perspective view of a bra and panty set.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; the panty being shown beside the bra instead of beneath it, for clarity of illustration; and,

FIG. 7 is a bottom plan view thereof.
